(57) CLAIM

The ornamental design of a glue gun, as shown and described.

DESCRIPTION

FIG. 1 is a right front perspective view of our new design;
FIG. 2 is a front view thereof;
FIG. 3 is a rear view thereof;
FIG. 4 is a right side elevational view thereof, the opposite side being a mirror image thereof;
FIG. 5 is a top view thereof; and,
FIG. 6 is a bottom view thereof.

The broken lines illustrate portions of the glue gun which form no part of the claimed design.
